CLAIM

The ornamental design for an umbrella pouch, as shown and described.

DESCRIPTION

FIG. 1 is a top front perspective view of an umbrella pouch; FIG. 2 is a front elevation view thereof, the rear elevation view is a mirror image thereof; FIG. 3 is a left elevation view thereof; FIG. 4 is a right elevation view thereof; FIG. 5 is a top plan view thereof; and, FIG. 6 is a bottom plan view thereof.

The broken lines shown in the drawings illustrate portions of the umbrella pouch that form no part of the claimed design. The cutaway symbols illustrated in break lines in the drawings indicate a symbolic break in the length of the design for the umbrella pouch indicating an indeterminate length. The appearance of any portion of the article between the break lines forms no part of the claimed design.
